(57) **CLAIM**

The ornamental design for an LED lamp, as shown and described.

DESCRIPTION

FIG. 1 is a front perspective view of an LED lamp showing our new design;

FIG. 2 is a top plan view thereof;

FIG. 3 is a right side elevational view thereof, the left side elevational view being a mirror image thereof; and,

FIG. 4 is a bottom plan view thereof.

The broken lines in the Figures show portions of the LED lamp which form no part of the claimed design. The shade lines in the Figures show contour and not surface ornamentation.
